UNITED STATES PATENT OFFICE.

EUGENE STEBBINGS, OF DES MOINES, IOWA.

DISPENSING DEVICE.

Application filed October 19, 1925. Serial No. 63,322.

The object of my invention is to provide a fountain brush structure of simple, durable and inexpensive construction. More particularly, it is my object to provide a container and a brush supported thereby with means for ejecting the contents of the container through the brush, said device being of novel construction to facilitate inexpensive manufacture and assembling.

With these and other objects in view, my invention consists in the construction, arrangement and combination of the various parts of my fountain brush structure, whereby the objects contemplated are attained, as hereinafter more fully set forth, pointed out in my claims, and illustrated in the accompanying drawings, in which:

Figure 1 is a perspective view of a fountain brush structure embodying my invention.

Figure 2 is a detail, sectional view taken on the line 2—2 of Figure 1.

Figure 3 is a transverse, sectional view taken on the line 3—3 of Figure 2.

Figure 4 is a large, sectional view illustrating certain of the details of the device; and

Figure 5 is a sectional view of the lower end of a modified form of my device.

In the accompanying drawings, I have used the reference numeral 10 to indicate generally a cylindrical casing which is open at what may for convenience be called its lower end, and is open at its upper end, except for a narrow flange 11.

At the lower end of the casing 10, it is provided with a folded over portion 12 forming an external rib. Spaced upwardly from the lower end of the casing 10 the casing is formed with an external rib 13 and an internal groove 14, the purposes of which will be hereafter referred to.

I provide a closure for the upper end and a plunger and means for actuating the plunger, which will now be described.

A screw-threaded rod 15 has on one end a suitable handle 16. The portion of the rod adjacent to the handle, as at 17, is not screw-threaded and has mounted thereon a closure disc 18, in which the portion 17 is rotatably mounted.

The closure disc 18 is held in place by a small collar 19.

Mounted on the screw-threaded rod 15 by a screw-threaded connection is a plunger 20

against the face of which is placed a felt disc or washer or the like 21.

In the assembling of the device, a washer or gasket 22 is placed just inside the flange 11. The plunger 20 and disc 21 secured thereto in any suitable way are screwed onto the rod 15 until they are adjacent to the collar 19.

The device is then inserted into the lower open end of the casing 10 and moved longitudinally of the casing until the closure disc 18 engages the packing 22 adjacent to the flange 11. The casing is then filled with contents 23, which may be shoe polish in the form of a paste or paste of any other suitable character.

I provide bristles 24 mounted in a shell 25, which is in the form of a cylinder having the closed end 26 except for the central opening 27.

The material of the end 26 is bent downwardly around the central opening to form an annular flange, which is inclined slightly outwardly from its upper portion. The flange is indicated at 28.

Between the flange 28 and the outer wall of the shell 25 is formed an annular channel to hold the inner ends of the bristles.

At the lower end of the shell 25, the wall thereof is folded inwardly as at 29 to form an internal rib to direct the bristles inwardly to catch the material dispensed.

The wall of the shell 25 has opposite slight projections 30, as shown in Figure 4, adapted to fit into the groove 14 for holding the shell against accidental movement.

On the outside of the lower end of the casing 10 is mounted a sleeve 31 having its lower end open as at 32, as shown in Figure 1, and having its upper end in-turned to form the internal rib 33, which slides on the casing 10 and is adapted to engage the rib 12 to prevent the accidental removal of the sleeve 31.

When the device is not in use, the sleeve is slid downwardly until the bristles are wholly contained therein.

When it is desired to use the brush, the sleeve 31 is slid upwardly until the lower ends of the bristles project from the sleeve, whereupon the handle 16 is rotated for forcing the plunger 20 downwardly on the screw-threaded rod 15 and thus forcing the contents 23 of the container through the opening 27 in the upper end or head 26 of the shell 25 into the center of the bristles.

The brush may then be used for applying the paste to the shoes or for any other purpose for which the contents 23 are adapted.

It will be noted that I have provided a 5 very simple structure for a device of this kind and I call particular attention to the construction which facilitates the assembling of the parts and mounting them so that they may be readily disassembled.

10 It will be seen that the device may be taken apart by pulling out the shell 25 and thereupon the rod 15 with the plunger 20 and the closure member 18 assembled thereon can be shoved out through the lower open 15 end of the casing.

Such changes may be made in the details of the structure of my device as do not depart from the essential features and spirit of my invention as defined in the claims, and 20 it is my intention to cover by my claims, any modified forms of structure or use of mechanical equivalents, which may be reasonably included within their scope.

For example, by the use of the terms 25 "brush" or "bristles" herein, I intend to include an absorbent member, sponge or any device which might for the purpose be equivalent to a brush or bristles.

In Figure 5, I have shown a sponge 34 to 30 replace the brush 24.

Likewise by the use of term "paste," I would include liquids of any kind, which may be appropriately used with my device.

I claim as my invention:

35 1. A dispenser of the class described com-

prising a tubular casing noncircular in cross section and having an inturned flange at its upper end, a disk adjacent said flange, a gasket between said disk and said flange, a piston actuating rod rotatably but non-slidably mounted in said disk and a piston, screw threadedly mounted on said rod whereby turning movement of said rod causes said piston to dispense material from said casing and maintains said disk tightly 45 against said gasket and flange.

2. A structure of the class described comprising a tubular casing, noncircular in cross section and having an inturned flange at its upper end, a disk adjacent said flange, 50 a gasket between said disk and said flange, a piston actuating rod rotatably mounted in said disk, a collar on said rod adjacent said disk and a piston, screw threadedly mounted on said rod whereby turning movement of said rod causes said piston to dispense material from said casing and said collar maintains said disk tightly against 55 said gasket and flange.

3. A structure of the class described comprising a tubular casing, an inturned flange at the upper end thereof, a disk within said casing and adjacent said flange, a gasket between said disk and said flange, a piston actuating rod rotatably but nonslidably 60 mounted in said disk, a collar secured to said rod adjacent said disk and a piston, screw threadedly mounted on said rod. 65

Des Moines, Iowa, October 7, 1925.

EUGENE STEBBINGS.
